2 Sheets-Sheet 2

8 FIG. 8 8 FIG. 10

UNITED STATES PATENT OFFICE.

DAVID GUELBAUM, OF SYRACUSE, NEW YORK.

UNIVERSAL GRAIN-CUTTING MACHINE.

Application filed April 15, 1925. Serial No. 23,300.

To all whom it may concern:

Be it known that I, DAVID GUELBAUM, a citizen of the United States, and a resident of Syracuse, in the county of Onondaga and State of New York, have invented a certain new and useful Universal Grain-Cutting Machine, of which the following is a specification.

My invention of a "universal grain cutting machine" has for its object the clean-cutting of grains, without cracking or crushing of the grains and without powdered wastage, by means of stationary and rotating vertical shearing knives, and it is made universal in its action by having the grain passages between its shearing knives made adjustable to a fraction of one hundredth of an inch, while the machine is in full running, so that on the same machine any kind of grain may be cut, small or large, such as wheat, rye, oats, barley, corn and even beans, coarse or fine, as desired. And reference is here made to the applicant's previous patents on: "grain cutting machine" #1,451,217, issued April 10, 1923, and on "grain cutting machine with automatic scoops" #1,456,003, issued May 22, 1923, my present machine differing from said preceding ones by said universality of its action, by its shearing knives made detachable and by its adaptability to varying velocities of the rotor knives.

My invention comprises the above novel features, embodied in combinations and constructions as hereinafter set forth and claimed, and as illustrated in the accompanying drawings, in which similar characters designate the same corresponding parts in all the views.

Fig. 1 is a vertical section of my universal grain cutting machine in its ensemble.

Fig. 2 is a top view of same, with part of the hopper cut off.

Fig. 3 is a magnified part view of the lower ring with the cast on diametrically opposite pairs of lugs, showing the shaft and eccentricities of the grain passages adjusting mechanism passing between said pairs of lugs.

Fig. 4 is a magnified part view of the outer lugs on bottom of the stationary cylinder, holding said shaft of the grain passages adjusting mechanism.

Fig. 5 is a magnified sectional bottom view on line 12—12 of said inner and outer lugs,

showing the end of said regulating shaft with its eccentric and bearing plates.

Fig. 6 is a magnified view of said inner and outer bearing plates.

Fig. 7 is a part cross section on line 1—1 of the stationary and rotor cylinders, showing the attached shearing knives and scoops.

Fig. 8 is a magnified part elevation on line 10—10, in development, of the inner surface of the stationary cylinder, showing the way the knives are fastened to said cylinder with the baffles fastened to the rings at top and bottom of said cylinder.

Fig. 9 is a similar magnified part elevation on line 10—10, in development, of the outer surface of the rotor cylinder, showing the way the knives and baffles are fastened to said cylinder.

Fig. 10 is a magnified part vertical section on line 2—2 of the rotor and stationary cylinders with the shearing knives between, showing the upper ring with its ball bearings resting on top of the stationary cylinder and the lower ring at the bottom of said cylinder, and the scoops attached to the dome of the rotor cylinder.

Fig. 11 is a magnified elevation of the operating mechanism, closing and opening the grain passages as desired.

Fig. 12 is a magnified part vertical section of the inner and outer lugs, showing the end of the shaft with the eccentric and bearing plates of the grain passages adjusting mechanism.

As seen on Figs. 1 and 2, 1 is a stationary cylindrical grain hopper, flanged at the top and tapered at its bottom, having a cast on inner flange 2 and provided with outside supporting brackets 3. To the inner flange 2 is bolted on the bottom flange 4 of the stationary cylinder 5, having longitudinal slots with beveled edges outside, Figs. 7 and 10, for the grain from the hopper 1 to be easily scooped into said slots.

To the solid portions between the slots of said cylinder 5 are fastened the stationary knives 6, Figs. 7, 8 and 10, projecting partly above and below the cylinder 5, as shown on Figs. 8 and 10. On its top the cylinder 5 carries the ring 7 of same diameter and thickness as the cylinder 5 and resting on ball bearings, Fig. 10, while at the bottom of cylinder 5 there is similar ring 8, Figs. 8 and 10, both these rings being connected together by the baffles 9, fastened to the rings, 110

as shown on Fig. 8. By turning slightly the ring 8 to the right or the left, the baffles 9 will approach towards or recede from the knives 6, thus closing or opening the grain 5 passages as much as desired.

Inside the stationary cylinder 5 is located the rotor cylinder 10, Figs. 7 and 10, having longitudinal slots similar to the stationary cylinder 5, but much wider ones with its 10 solid portions between correspondingly narrower and reenforced by the inside ribs 11, as shown on Figs. 7 and 10. To these solid portions of the rotor 10 are fastened the rotor knives 12, Figs. 7 and 9, while covering part of the wide slots are the baffles 13, fastened over the slots to the top and bottom of the rotor 10, as shown on Figs. 9 and 10.

While the function of the baffles 9, Fig. 8, 20 on the stationary cylinder 5, is to regulate the width of the grain passages for different sizes of grains, the object of the baffles 13, Fig. 9, on the rotor cylinder is to adapt the machine to various velocities of 25 the rotor: at high velocities of the rotor knives, the baffles 13 may be dispensed with entirely and the wide passages in the rotor cylinder left fully open, in order to allow enough time for the grains to be scooped 30 into the stationary passages and protrude sufficiently, before the rapid moving knives 12 pass by; while at moderate velocities of the rotor cylinder 10, wider or narrower baffles 13 may be used to cover up part of 35 the wide passages in the rotor cylinder to prevent some of the grains from passing thru prematurely.

At its top the rotor cylinder 10 terminates into the cast on dome 14, Figs. 1 and 10, 40 overlapping and protecting the top ring 7 and provided at its centre with the hub 15, Figs. 1, 2 and 10. At its circumference the dome 14 is provided with the cast on projections 16, Figs. 2 and 10, to which are fastened the scoops 17, Figs. 1, 2, 7 and 10, so that while the rotor cylinder 10 is revolving inside of the stationary cylinder 5, the slanting scoops are revolving around the outer surface of the stationary cylinder 5, scooping 45 up the grain in the hopper and forcing it thru the beveled vertical passages of the stationary cylinder 5 to be caught up by the revolving knives 12 of the rotor 10.

In order to impart a slight movement to 55 the upper and lower rings 7 and 8 with the fastened to them baffles 9, Figs. 8 and 10, thus adjusting the grain passages between said baffles 9 and the adjacent knives 6 and then hold the baffles 9 immovably in that desired fixed position, the lower ring 8 is provided with the two pairs of lugs 18, Figs. 3 and 12, diametrically opposite each other. Between these lugs passes the shaft 19 with the eccentric 20 at each end, key seated and 60 setscrewed at 180° to each other, as on Fig.

3, these eccentrics fitting in exactly between each pair of lugs 18. The shaft 19 is supported by the two outer bearing plates 23, Fig. 6, at each end of the shaft 19, Figs. 12 and 5, fastened to the lugs 22, Figs. 12, 4 70 and 5, on the stationary cylinder 5; and also by the two inner bearing plates 21, Fig. 6, fastened to the lugs 18, Figs. 3, 12 and 5, on the lower ring 8.

The shaft 19 is held in its fixed position 75 by the outer bearing plates 23 and can only turn on its axis, while the inner bearing plates 21 are provided with oblong holes, allowing a slight movement of the lower ring 8, Figs. 12 and 5 relative to the shaft 80 19. Turning the shaft 19 slightly one way or the other, the eccentrics 20, Fig. 3, will push the lugs 18 with the lower ring 8 and the fastened to it baffles 9, Fig. 8, to the right or to the left, closing or opening more 85 or less the grain passages of the stationary cylinder 5, without interfering with the rotation of the rotor knives.

In order to regulate the grain passages 90 micrometrically, to a fraction of one hundredth of an inch, the bent brace 24, Figs. 2 and 11, is fastened to the outside of the hopper 1, holding within it the screw 25 which can only turn but cannot move lengthwise, while the square nut 26 on that screw, 95 butting flatly against the brace 24, can only move lengthwise but cannot rotate when the screw 25 is turned.

The bent lever 27, Figs. 1 and 11, fastened to the end of the shaft 19, passes upward over the brace 24, while a projecting pin on the square nut 26, Figs. 1 and 11, passes thru the longitudinal slot in the brace 24 into the longitudinal slot in the lever 27, Fig. 11, so that turning the screw 25 by the 100 handwheel 28, the square nut 26, moving along the brace 24, will turn the lever 27 to the right or to the left, towards the position shown in dash and dot, Fig. 11, and with it the shaft 19 with the eccentrics 20, Fig. 3, 105 110 and impart a minute movement to the lower and upper rings 8 and 7 with the fastened to them baffles 9, Fig. 8, towards or from the knives 6.

To the brace 24, outside, is fastened the 115 arc sector 29, Fig. 11, passing over the lever 27 to which it is connected by a bolt with a thumb nut, Figs. 1 and 2, the bolt moving along the circular slot in the arc sector 29. By tightening the thumb nut the lever 27 120 is held fixed in any desired position and with it the shaft 19 with its eccentrics. Divisions marked on the arc sector 29, Fig. 11, indicate the opening width of the grain 125 passages for any position of the lever 27 in hundredths of an inch.

To the top flange of the grain hopper 1 is bolted on the cover 30, Fig. 1, stiffened with ribs and provided with the cast on grain chute 31, the central hub 32 and the brackets 130

for pillow blocks to rest on, as shown on Fig. 1.

Thru the hub 32 of said cover and the hub 15 of the rotor dome 14, Fig. 1, passes the 5 gudgeon 34, key seated in the rotor hub 15, but free to turn in the cover hub 32. The gudgeon 34 with the dome 14 is carried by the ball bearing support 35 on top of the cover 30. On top of the gudgeon 34 is key 10 seated the bevel pinion 36 engaging the bevel gear 37 on the horizontal shaft 38 driven by the step pulley 39 and held in pillow blocks bolted on to the brackets 33 on top of the cover 30, as shown on Fig. 1.

15 Instead of the belt drive shown on Fig. 1, a direct electric driving motor may be applied to the gudgeon 34.

What I claim is:

1. A universal grain cutting machine, 20 comprising a cylindrical grain hopper with an open top and a tapered bottom flanged inside and having a fastened on cover on top, a stationary cylinder with an open top and a flanged bottom fastened to the bottom 25 flange of said hopper and having longitudinal slots for passage of the grain and knives fastened inside along said slots, a ring on top of said stationary cylinder resting on ball bearings and a ring on bottom of said 30 cylinder connected to said top ring by baffles, means for turning said rings with the fastened on baffles for regulating said grain passages, a rotor cylinder inside of said stationary cylinder with an open bottom 35 and a closed dome on top with a hub in centre and having longitudinal slots with fastened on knives and baffles outside rotating in sliding contact over the knives and baffles on said stationary cylinder, means for supporting 40 and rotating said rotor cylinder, means for micrometrically adjusting and indicating the opening width of said grain passages, substantially as and for the purpose specified.

2. A universal grain cutting machine, 45 comprising a cylindrical grain hopper with an open top and a tapered bottom flanged inside and having a fastened on cover on top provided with a hub in centre and with a ball bearing support, a stationary cylinder 50 inside of said hopper having an open top and a flanged bottom fastened to the bottom flange of said hopper and having longitudinal slots with fastened on knives, a ring on top of said cylinder resting on ball bearings and a ring at the bottom of 55 said cylinder connected to said top ring by inside baffles, means for turning said rings for regulating the grain passages between said knives and baffles, a rotor cylinder inside of said stationary cylinder with an open bottom and a closed dome on top with a hub in centre and having longitudinal slots with fastened on knives and baffles outside 60 rotating in sliding contact over the knives and baffles on said stationary cylinder, means 65

for supporting and rotating said rotor cylinder, means for micrometrically adjusting and indicating the opening width of said grain passages, substantially as and for the purpose set forth. 70

3. A universal grain cutting machine, 75 comprising a cylindrical grain hopper with an open top and a flanged bottom fastened to the bottom flange on said hopper and having longitudinal slots for grain passage and knives fastened inside and provided at its bottom flange with two pairs of lugs for 80 supporting the grain passages regulating shaft, a ring on top of said stationary cylinder resting on ball bearings and a ring at the bottom of said cylinder connected to said top ring by baffles, means for turning said 85 rings for regulating the grain passages between said knives and baffles, a rotor cylinder inside of said stationary cylinder with an open bottom and a closed dome on top with a hub in centre and having longitudinal slots with fastened on knives and baffles outside rotating in sliding contact over the knives and baffles of said stationary cylinder, means for supporting and rotating said 90 rotor cylinder, means for micrometrically 95 adjusting and indicating the opening width of said grain passages, substantially as and for the purpose described.

4. A universal grain cutting machine, 100 comprising a cylindrical grain hopper with an open top and a tapered bottom flanged inside and a cover on top, a stationary cylinder inside of said hopper with an open top and a flanged bottom fastened to the bottom flange of said hopper and having longitudinal slot with knives fastened inside and provided at its bottom flange with two pairs of lugs for shaft support, and a ring on top of said cylinder resting on ball bearings and a ring at the bottom of said cylinder 110 connected to said top ring by fastened on baffles and provided with two pairs of lugs in line with the lugs on the bottom flange of said cylinder combinedly supporting a shaft having an eccentric at each end for turning said rings with the fastened to them baffles and thus regulating the grain passages between the knives and the baffles, a rotor cylinder inside of said stationary cylinder with an open bottom and a closed dome 115 on top with a hub in centre and having longitudinal slots with fastened on knives and baffles rotating in sliding contact over the knives and baffles on said stationary cylinder, means for supporting and rotating said rotor cylinder, means for micrometrically 120 adjusting and indicating the opening width of said grain passages, substantially as and for the purpose specified.

5. A universal grain cutting machine, 125

comprising a cylindrical grain hopper with an open top and a tapered bottom flanged inside with a fastened on cover on top having a hub in centre with a ball bearing support, a stationary cylinder inside of said hopper with an open top and flanged bottom fastened to the bottom flange of said hopper and having longitudinal slots with fastened on knives inside, a ring on top of 5 said stationary cylinder resting on ball bearings and a ring at the bottom of said cylinder connected to said top ring by fastened on baffles, means for turning said rings for regulating the grain passages between said 10 knives and baffles, and a rotor cylinder inside of said stationary cylinder with an open bottom and a closed dome on top provided at its circumference with projections and fastened on scoops for scooping the grain 15 from the hopper into the longitudinal slots on said stationary cylinder and having longitudinal slots with fastened on knives and baffles rotating in sliding contact over the knives and baffles inside of said stationary 20 cylinder and having a hub in the centre of said dome with a gudgeon passing thru the hub on the cover of said grain hopper and thru the ball bearing support on top of 25 said cover for supporting and rotating said 30 rotor cylinder and dome with its fastened on scoops, means for micrometrically adjusting and indicating the opening width of said grain passages, substantially as and for the purpose set forth.

35 6. A universal grain cutting machine, comprising a cylindrical grain hopper with an open top and a tapered bottom flanged inside with a cover on top, a stationary cylinder inside of said hopper with an open top and flanged bottom fastened to the bottom flange of said hopper and having longitudinal slots with fastened on knives and provided with two pairs of lugs on its bottom flange holding the grain passages regulating shaft with its operating lever, a ring 40 on top of said cylinder resting on ball bearings and a ring at the bottom of said cylinder connected to said top ring by fastened on baffles and provided with two pairs of lugs holding said grain passages regulating 45 shaft with its operating lever, a rotor cylinder inside of said stationary cylinder with an open bottom and a closed dome on top with a supporting hub and gudgeon in centre and having longitudinal slots with 50 fastened on knives and baffles and with fastened on scoops on said dome, and a bent horizontal brace fastened to said grain hopper outside and holding a screw between its ends with a nut moving along said screw 55 and having a projecting pin passing thru a slot in said brace and thru a slot on the operating lever of said grain passages regulating shaft for micrometrically turning said lever along a fastened to said brace circular arc with marked on divisions indicating the corresponding opening width of said grain passages, substantially as and for the purpose described.

In testimony whereof, I have hereunto 60 signed my name, at Syracuse, in the county of Onondaga, and State of New York, this 14 day of April, 1925.

DAVID GUELBAUM.
